UNITED STATES PATENT OFFICE.

EDWIN FULTON POTTENGER, OF VANCOUVER, BRITISH COLUMBIA, CANADA.

INTERNAL-COMBUSTION ENGINE.

1,120,533.

Specification of Letters Patent.

Patented Dec. 8, 1914.

Application filed July 16, 1913. Serial No. 779,304.

To all whom it may concern:

Be it known that I, EDWIN FULTON POTTENGER, a subject of the King of Great Britain, and a resident of the city of Vancouver, 5 in the Province of British Columbia, Canada, have invented certain new and useful Improvements in Internal-Combustion Engines, of which the following is a specification.

10 My invention relates to improvements in internal combustion engines, with more particular reference to the cylinder thereof, and the object of my invention is to devise an internal combustion engine of the two- 15 cycle type, which shall have two explosions per revolution, that is, an explosion on the down stroke and an explosion on the up stroke, thus gaining a large increase of power without any material addition to the 20 weight or dimensions of the engine being necessary.

A further object is to devise an internal combustion engine which shall be valveless, and in which the burned gases shall be efficiently cleared out of the cylinder before 25 the fresh explosive charge is admitted, thus obviating the possibility of any of the explosive mixture being driven out along with the exhausting gases, as is common in two 30 cycle engines of the present type, and making my engine most economical as regards fuel consumption.

A still further object is to devise an internal combustion engine which shall be of 35 the minimum weight for a given power without sacrificing strength of construction to attain this purpose, and having the working parts reduced to a minimum, thus making the engine particularly well adapted to 40 aviation purposes, while at the same time equally adaptable to any other purposes for which internal combustion engines are used.

I attain these objects by the construction 45 illustrated in the accompanying drawings in which—

Figure 1 is a sectional elevation on the vertical center line of my engine. Fig. 2 is a sectional elevation of the sleeve through the slots. Fig. 3 is an outside elevation of 50 the sleeve. Fig. 4 is a sectional elevation of the fixed-piston. Fig. 5 is an outside elevation of the fixed piston. Fig. 6 is a detail plan view of one of the piston holders.

Fig. 7 is a side elevation of the piston holder. Fig. 8 is a front end view of 55 Fig. 7.

Similar letters of reference indicate similar parts throughout the several views.

a is the cylinder wall of my engine.

b is the water circulation space. 60

c is the bore of the cylinder.

d is the fixed piston, annular in plan section, and firmly held to the cylinder wall *a* by the piston holders *e*, which are adapted to pass through the cylinder wall and the 65 sliding sleeve and into the fixed piston, as shown in Fig. 1. The piston holders *e* have flanges on their outer ends, by which they are fastened to the cylinder wall, thus making a rigid connection between the cylinder 70 and the fixed piston. The piston *d* is formed as a cylinder, and its ends are closed by the heads *f* and *g*, which are concave in form and are screwed into the piston as shown in Fig. 4. Openings *w* are formed in *d*, as 75 shown in Fig. 4, to receive the holders *e*.

h is the sliding sleeve, or moving piston, which incloses the fixed piston *d*, and moves up and down in the bore *c* and between the outside of the fixed piston *d* and the inside 80 of the cylinder wall *a*. *h* is formed as a cylinder, the thickness of its walls being such that it will have a good working fit on the body of the fixed piston and in the bore of the cylinder. The ends of *h* are 85 closed by the heads *i* and *j*, which are concave on their inner faces and are screwed into *h* as shown in Fig. 2, to be perfectly tight to prevent leakage of the explosive gases. 90

k are piston rings fitted on the outside of the sleeve *h*, toward its top and bottom ends.

l are slots formed in the sleeve *h*, opposite to each other, to allow for the sleeve passing over the piston holders *e*, and also 95 to act as inlet and exhaust ports for the air used in clearing the burned gases out of the explosion chambers, as hereinafter more particularly explained.

m are the air inlet ports. 100

n are the air inlet pipes.

o are the exhaust ports.

p are the exhaust pipes.

q are the spark plugs.

r are the fuel injection valves. 105

s is the fuel supply pipe.

2
 t is the connecting rod.
 u is the crank shaft.

v is the crank case.

Having now indicated the principal parts
 5 of my invention, I will now describe its
 operation.

Referring particularly to Fig. 1, in which
 the engine is shown on the down stroke, it
 will be seen that there are two explosion
 10 chambers within the sliding sleeve h, one
 chamber being the space inclosed within the
 sleeve between the head f of the fixed piston
 d and the head i of the sleeve h and the other
 or lower chamber being the space inclosed
 15 within the sleeve between the head g of the
 fixed piston d and the head j of the sleeve h
 so that if an explosive mixture be admitted
 alternately by the injection valves r and ig-
 nited by the spark plugs q, an explosion
 20 will take place in the top and bottom ex-
 plosion chambers alternately, in other words
 an explosion will occur in the lower chamber
 to drive the sleeve down, and an explosion
 will occur in the upper chamber to drive
 25 the sleeve up. The connecting rod being
 secured to the sleeve in an approved mech-
 anical manner, two effective explosions or im-
 pulses are thus directed on the crank shaft
 during one revolution.

30 To provide for the effective clearing of
 the burned gases out of the explosion cham-
 bers, the air inlet ports m and exhaust ports
 o are provided. These pass through the
 35 walls of the cylinder a, and are in communi-
 cation, respectively, with the air inlet pipes
 n, and the exhaust pipes p. Referring fur-
 ther to Fig. 1, it will be seen that, on the
 40 down stroke the slots l are open to the inlet
 and exhaust ports m and o, being full open
 when the stroke is completed. As soon as
 the slots l begin to open the ports m and o,
 the air rushes in through m and passing all
 45 through and around the explosion chamber,
 rushes out through the exhaust port o, driv-
 ing the burned gases out with it, all as indi-
 cated by the arrow heads in Fig. 1. This
 continues until the ports m and o are cov-
 50 ered by the walls of the sleeve on the up
 stroke, the fresh charge being admitted
 when the ports are closed, when compres-
 sion begins. This action is duplicated in the
 upper explosion chamber, and is carried on
 55 alternately as long as the engine is running.

The air for clearing the explosion cham-
 bers is supplied thereto under pressure by
 any approved mechanical method best
 adapted to the purpose. The fuel mixture
 is injected into the chambers by any ap-
 60 proved system, the means shown in Fig. 1
 being merely for the purpose of illus-
 tration. The internal lubrication of the engine
 is effected by the combined "splash" and
 force feed system of lubrication.

It will be seen, further, that I have de-
 65 vised an engine which shall be valveless, and

in which the "scavenging" or clearing of
 the burned gases out of the explosion cham-
 bers is accomplished effectively before the
 charge is admitted, thus obviating the possi-
 bility of any of the charge being carried out
 70 with the exhausting gases, which is a direct
 cause of loss of power and increased con-
 sumption. In my engine, there is no possi-
 bility of leakage of the mixture once it is
 admitted to the explosion chamber, conse-
 75 quently the maximum amount of power is
 obtained with the minimum consumption of
 fuel. It will be seen still further that, as
 my engine will develop twice as much power
 as a two cycle engine having one explosion
 80 per revolution; and of the same relative di-
 mensions, a smaller engine will be required
 for a given power, and therefore, a lighter
 engine, so that my engine is particularly
 well adapted for aviation purposes and
 85 other purposes where weight is a considera-
 tion, while at the same time its simplicity
 makes it adaptable to all purposes for which
 internal combustion engines are used.

What I claim as my invention is—

1. In a two cycle internal combustion en-
 gine, the combination with the cylinder, of
 a movable piston fitting within the cylinder
 and having opposing longitudinal slots, por-
 90 tions projecting inwardly from the cylinder
 through the slots, a stationary piston fit-
 ting the movable piston and supported by
 the inwardly projecting portions and means
 extending through said inwardly projecting
 95 portions for feeding the fuel into the space
 at each end of the explosion chamber, as
 and for the purpose specified.

2. In a two cycle internal combustion en-
 gine, the combination with the cylinder hav-
 ing an exhaust port in proximity to each
 100 end, of a movable piston fitting the cylinder
 and having diametrically opposite longi-
 tudinal slots the ends of which are designed
 to be brought alternately into alinement
 with the exhaust ports, stationary projec-
 105 tions extending inwardly from the cylinder
 through the slots, and a stationary piston
 supported thereby within the movable pis-
 ton and fitting the same, as and for the pur-
 pose specified.

3. In a two cycle internal combustion en-
 gine, the combination with the cylinder hav-
 ing an exhaust port in proximity to each end
 thereof, and opposing air inlet ports, of
 a movable piston fitting the cylinder and
 110 having longitudinal slots the ends of which
 are designed to be carried into alinement
 with an opposing exhaust and air inlet port
 of the cylinder, projections extending from
 the cylinder through the slots, and a sta-
 115 tionary piston supported thereby and fitting
 the movable piston, as and for the purpose
 specified.

4. The combination with a two cycle in-
 120 ternal combustion engine having a cylinder

a movable piston and a stationary piston within said cylinder, of means extending through the walls of said cylinder and movable piston for supporting said stationary piston, and means for introducing an explosive charge through said stationary piston.

5. The combination with a two cycle internal combustion engine having a cylinder 10 a movable piston and a stationary piston, and a pair of combustion chambers, of means extending through the walls of the cylinder and said movable piston for introducing an explosive charge into the combustion chambers through said stationary piston.

15. In a two cycle internal combustion engine, the combination with the engine cylinder, of a hollow movable piston fitting the cylinder, a stationary piston fitting within the movable piston so that the movable piston is slidale longitudinally thereon, means

for supporting the stationary piston in a stationary position extending through the walls of said cylinder and piston, and means for feeding the charge through said stationary piston.

25. 7. In an internal combustion engine as described, the combination with a cylinder and a movable piston fitting within the cylinder, of a stationary piston the ends of 30 which are substantially concave in shape supported within the said movable piston, and firing means adapted to extend through the ends of the said stationary piston to fire the charge in each explosion chamber 35 alternately, as and for the purpose specified.

Dated at Vancouver, B. C., this 24th day of June, 1913.

EDWIN FULTON POTTERER.
